UNITED STATES PATENT OFFICE.

CHARLES T. MITCHELL, OF SPENCERPORT, NEW YORK.

COMBINATION SUIT-HANGER.

1,223,194.

Specification of Letters Patent. Patented Apr. 17, 1917.

Application filed March 25, 1916. Serial No. 86,644.

To all whom it may concern:

Be it known that I, CHARLES T. MITCHELL, a citizen of the United States, residing at Spencerport, in the county of Monroe and State of New York, have invented certain new and useful Improvements in Combination Suit-Hangers; and I do hereby declare the following to be a full, clear, and exact description of the invention, such as will 10 enable others skilled in the art to which it appertains to make and use the same.

This invention relates to new and useful improvements in combination suit hangers and the principal object of the invention is 15 to provide a device which forms a coat and trouser hanger.

Another object of the invention is to provide a device which may be easily and cheaply constructed of wood, metal or any 20 other suitable material and will hold the clothing in their proper shape.

With these and other objects in view, the invention consists in the novel combination and arrangement of parts which will be 25 fully set forth in the following specification and accompanying drawings, in which:—

Figure 1 is a perspective view of a suit hanger constructed in accordance with this invention.

Fig. 2 is a side view in elevation of the device showing the same partly open, and

Fig. 3 is a top plan view of the hanger.

Referring to the drawings the numeral 1 designates as an entirety the main body of 35 the device consisting of the arcuate body portion 2 having a suitable head 3 formed at each end. These heads extend outwardly from one of the flat faces of the body portion and are formed with the inwardly extending lugs 4, the ends of which are formed with the bevel faces 5. Extending through the body portion 2 and centrally thereof is the stem 6 of a suitable hook designated generally by the numeral 7, the upper end 40 of which is provided with a hooked portion 8 by means of which the dev. 3 is hung. Pivoted beneath one of the ears 4 by a suitable pivot pin 9 is the coöperating clamp member 10 which is arcuate 45 to conform to the shape of the body and

consists of the body portion 11 having formed at opposite ends the longitudinally extending ears 12 one of which is provided with an aperture for the reception of the pivot pin 9, while the opposite ear is adapted to engage beneath the projection 4 at the opposite end of the main body of the hanger. The ends of the body portions 11 are beveled as at 13 so as to engage the beveled faces 5 and prevent the clamp member from moving 60 downwardly beyond a predetermined point. As illustrated in Fig. 3, it will be seen that a space 14 is formed between the adjacent faces of the body and clamp member which is of a sufficient width to receive the thickness of the trousers, the ends of which are placed therein.

In use, it will be seen that the trousers are placed with their lower ends upwardly and the same are slipped into place when the 70 clamp member is in the raised position illustrated in Fig. 2. Upon swinging the clamp member downwardly it will be seen that the trousers will be firmly clamped in place between the clamp member and body and thus 75 the device will hold the trousers extended, thereby insuring the retaining of the crease. After the trousers have been placed in position, it will be evident that the coat may be slipped over the body and in this way an 80 entire suit may be hung up and will retain its shape.

While in the foregoing there has been shown and described the preferred embodiment of this invention, it is to be understood 85 that such changes may be made in the combination and arrangement of parts as will fall within the spirit and scope of the appended claim.

What is claimed is:—

A garment hanger comprising a curved body, a hook centrally of said body, a head extending outwardly from each end of the body and from one of the flat faces thereof, an inwardly extending lug on each head, a clamp member comprising a curved body, lugs on the ends of the curved body, said lugs being adapted to be positioned between the body of the hanger, and the lugs on the ends of the heads, and a pivot pin extending 100

through one pair of lugs to hold the clamp member in pivotal relation to the body, the clamp member and lugs on the body being provided with coöperating inclined faces to limit the downward movement of the clamp member with relation to the body.

In testimony whereof I affix my signature in presence of two witnesses.

CHARLES T. MITCHELL.
